DESIGN FOR A BELT BUCKLE

William Mandler, New York, N. Y.

Application June 7, 1940, Serial No. 92,877

Term of patent 3½ years

To all whom it may concern:

Be it known that I, William Mandler, a citizen of the United States of America, residing in New York city, in the Borough of Manhattan, county and State of New York, have invented a new, original, and ornamental Design for a Belt Buckle, of which the following is a specification, reference being had to the accompanying drawing, forming part thereof, wherein—

I claim:

The ornamental design for a belt buckle, substantially as shown.

WILLIAM MANDLER.
